UNITED STATES PATENT OFFICE.

PATRICK J. MADDEN, OF CHICAGO, ILLINOIS.

DESIGN FOR A BODY FOR DRINKING-FOUNTAINS.

SPECIFICATION forming part of Design No. 34,375, dated April 16, 1901.

Application filed October 22, 1900. Serial No. 33,975. Term of patent 7 years.

To all whom it may concern:

Be it known that I, PATRICK J. MADDEN, a citizen of the United States, residing at Chicago, in the county of Cook and State of Illinois, have invented and produced a certain new and original Design for the Body of a Drinking-Fountain, of which the following is a specification, reference being had to the accompanying drawings, which are made a part hereof, and in which—

Figure 1 is a side elevation of a drinking-fountain embodying the new design. Fig. 2 is a vertical section thereof on the line 22, Fig. 1.

A drinking-fountain of the new design comprises a flat horizontal slab A, of substantially rectangular outline, which at one side joins a vertical slab B of substantially rectangular outline, the remaining three sides of the slab A being bounded by a low wall C. The upper portion of the wall C is of substantially circular shape in vertical cross-section, and the outer face of the wall has a groove D of curved cross-section. The slab A is provided with circular openings E. The vertical slab B supports a plurality of brackets having or-

namental circular bases F, stems G proceeding first horizontally from said bases and then vertically, and circular tops H.

The leading essential features of the design are the horizontal slab A, the vertical slab B, joining one side of it, and the low wall C, surrounding the slab A on its three remaining sides. A minor feature of the design is the configuration of the wall C, including the rounded top thereof and the curved groove 35 in the outer face.

Other minor features are the circular openings through the slab A and the brackets, of substantially the shape shown and described, supported by the slab B.

Having described my invention, what I claim as new, and desire to secure by Letters Patent, is—

The design for the body of a drinking-fountain substantially as herein shown and described.

PATRICK J. MADDEN.
